UNITED STATES PATENT OFFICE.

DANIEL C. KNOWLTON, OF BOSTON, MASSACHUSETTS.

ELECTRICAL GAS-LIGHTER.

SPECIFICATION forming part of Letters Patent No. 402,332, dated April 30, 1889.

Application filed October 16, 1888. Serial No. 288,514. (No model.)

To all whom it may concern:

Be it known that I, DANIEL C. KNOWLTON, of Boston, in the county of Suffolk and State of Massachusetts, have invented a new and 5 useful Improvement in Electrical Gas-Lighters, of which the following, taken in connection with the accompanying drawings, is a specification.

My invention relates to improvements in 10 devices for igniting gas by electricity; and it consists in the adaptation of a fixed and a movable electrode placed in electrical circuit through an oscillating lever-arm of ingenious and simplified construction arranged to establish momentary contact of said electrodes 15 in the process of lighting the gas.

The electrodes in gas-lighters have been heretofore made similar to those illustrated; but the lever has been complex and costly, 20 while the valve arrangement operated by the same lever has a ratchet-and-pawl or similar arrangement for its operation, whereas in my device less expense and more simplicity are obtained with better results; also, by one 25 distinct movement of the lever the gas is shut off or turned on and ignited, whereas in those now in use two or more operations are required.

I attain my object by means of the mechanism 30 illustrated in the accompanying drawings, in which—

Figure 1 is a front elevation of the mechanism, the electrodes being apart after ignition of the flame. Fig. 2 is a side elevation 35 of the same. Fig. 3 is a rear view of lever and spring. Figs. 4, 5, and 6 exhibit modifications of the construction, while Figs. 7 and 8 are transverse and longitudinal sections of the modified levers.

40 1 is a burner of ordinary pattern.
2 is the socket for the tip.

3 is the tip, slotted as usual.

4 is a collar fixed in any suitable method 45 around the socket 2 and insulated from said socket.

5 is the electrode connected with the negative wire from the battery and caught on a lug, 6, of the collar 4.

7 is a socket for the valve-plug in the 50 burner 1.

8 is a valve-plug provided with the usual duct or passage for the gas.

10 is the gas-inlet.

12 is the lever fixed by the screw 13 to the 55 king 8.

15 is a stop-pin fixed to burner 1.

In my modified forms the lever 12 may be constructed with an arched slot, 14, to receive the said stop-pin.

16 is a plate-spring with an indented end 60 fixed at one end to the lever 12 and having the other end resting against stop-pin 15.

18 is the electrode, which is arranged around 65 the end of lever 12 and serves as the positive pole of the circuit.

The operation of my mechanism may be thus described: The gas passing through inlet 10 passes through the duct of the valve-plug 8, which is opened by turning lever 12 to the left, and the electrodes 5 and 18 are brought 70 in contact with each other by said lever 12, and the circuit is closed until some time after the lever has passed from a perpendicular position and thus charged to a high degree, and when the electrodes separate the resultant 75 spark readily ignites the issuing gas. When the lever 12 is as far as desired, the pin 15 holds it from further movement and keeps it in place by the spring 16 clutching it. When it is desired to shut off the gas by 80 movement of lever 12 to the right, the valve-plug 8 closes over the inlet 10, and any further movement to right or any swinging motion of the lever 12 is checked by pin 15 in a similar way to that described heretofore when 85 lever is moved to the left.

Having described my invention, what I desire to secure by Letters Patent, and claim, is—

A gas-burner and a cock controlling the 90 passage of gas through the same, in combination with a lever attached to said cock and pivoted thereby in said burner, a pair of electrodes attached to said burner and said lever, a fixed pin, and a notched spring attached to 95 said lever and engaging said pin, one of said notches being arranged to hold the cock open and the other to hold it closed by engaging with said pin, substantially as set forth.

In testimony whereof I have signed my name 100 to this specification, in the presence of two subscribing witnesses, on this 29th day of September, A. D. 1888.

DANIEL C. KNOWLTON.
